HIS ATT'Y.

Patented Apr. 19, 1927.

UNITED STATES PATENT OFFICE.

WALTER J. RUDOLPH, OF CHICAGO, ILLINOIS, ASSIGNOR TO THE IMPERIAL BRASS
MANUFACTURING COMPANY, OF CHICAGO, ILLINOIS, A CORPORATION OF ILLINOIS.

ATOMIZING CLEANER.

Application filed January 23, 1922. Serial No. 531,303.

My invention is concerned with what I call atomizing cleaners, and it consists fundamentally of a hand implement adapted to be connected with a source of air or other gas under pressure and having a nozzle through which said compressed air is discharged, together with a tube surrounding the nozzle and provided with an extension which may be placed in a pail of kerosene or other cleansing fluid, so that when the air is permitted to escape through the nozzle, it carries with it a spray of the oil, which, striking the surface to be cleaned, carries away with it the dirt and grime which accumulates on the part to be cleaned, such, for instance, as the engine of an automobile.

To illustrate my invention, I annex hereto a sheet of drawings, in which,

20 Fig. 1 is a side elevation of my apparatus with an ordinary air chuck connected thereto;

Fig. 2 is a central longitudinal section of the same;

25 Fig. 3 is a view similar to Fig. 1, but showing a modified construction, and modified portion being in central vertical section;

Fig. 4 is a detail, on an enlarged scale, on the line 4—4 of Fig. 2; and

30 Fig. 5 is a detail, on a still larger scale, on the line 5—5 of Fig. 2.

The body 10 of the device is in the form of a small casing having three diverging tubular portions, the front end having a large 35 internally-threaded opening 11 therein, into which is screwed the nut 12, which is preferably circular in cross section and milled on its periphery, and has the tube 13 secured therein and extending outwardly therefrom.

40 The nipple portion 14 is adapted to have the preferably flexible tube 15 secured thereon in the customary manner, and in use the end of the tube 15 is extended into the can 16 of kerosene or whatever cleaning fluid is 45 employed.

In the simplest form of my invention, illustrated in Fig. 3, the third arm or portion has an internally-threaded aperture 17 into which is screwed the threaded end of 50 the nipple 18, which has the flexible tube 19 fastened thereon and extending to any desired source of compressed air. The nipple 14 has the passage 20 therethrough opening into the part 11, so that the oil can flow out 55 through the tube 13, and the portion 17 has

the fine passage 21 therethrough terminating in the fine tube 22 secured in the body and formed a continuation of the passage 21. This tube 22 extends out to the end of the tube 13, and preferably has the short helically-coiled wire 23 secured thereon, and which co-operating with the inner surface of the tube 13 keeps them concentric. By screwing the nut 12 in and out, it will be obvious that the relative positions of the tubes 13 and 22 may be varied as is necessary to increase or diminish the amount of oil that will be sucked up through the tube 15 and out through the tube 13 by the vacuum effect produced by the compressed air 70 rushing out through the tube 22.

In the preferred form of my invention, which is designed primarily for use in garages and other places where air chucks are employed, for the nipple 18, adapted to be 75 connected to an ordinary tube 19, I substitute the nipple 24, likewise adapted to be threaded into the opening 17, and having the hexagonal portion 25 to which a wrench can be applied, adjacent the disk 26, against 80 which rests the packing ring 27, which ring is supported on the reduced, outer, tubular end 28 of the nipple 24. There is a passage 29 extending entirely through the part 24 and terminating in an enlarged portion 30, and extending across the outer end of this enlarged portion is the bar 31, which co-85 operates with the tubular end 32 of the chuck valve 33. The chuck 34, which is adapted to be connected with the hose 35 leading to a source of compressed air, is a well known article of commerce, and, per se, forms no part of my invention. As it seems 90 advisable to explain how the connection 24 co-operates with this chuck, I have illustrated its internal construction, where it will be seen that the passage through the stem 36 opens into the hollow body 37, in the inner 95 end of which is seated the helically-coiled expanding spring 38, the outer end of which co-operates with the reduced inner end 39 of the valve body 33. This body portion 37 has covering its preferably tapered outer end the rubber annulus 40, through which slides the tubular portion 32 of the valve 33. The 100 valve 33 has the tapered flange 41 adapted to co-operate with the correspondingly truncated conical portion 42 of the rubber ring 40 and the pressure of the spring 38 normally holds the valve seated on the rubber, 105 110

so that the air cannot pass through the small port 43 located at the base of the tube 32. The internally-threaded cap 44 screwed on the outer end of the body 34 clamps the ring 40 in place, forming an air-tight joint. When the chuck is forced against the end 30, the cross piece 31 engages the end of the tube 32 and forces the valve back against the resistance of the spring 38 to the position shown in full lines in Fig. 5, where it will be seen that the port 43 is opened and the air can flow through the implement.

As it would be difficult to manipulate the apparatus if the chuck has to be held independently by one hand, I provide the body 10 with a pair of ears 45 in which is pivoted the yoke or bail 46 having the nut 47 at the outer end thereof, through which nut is threaded the thumb screw 48 which has the disk 49 on its inner end, which is adapted to co-operate with the back of the chuck 34, as seen in Fig. 1. When the device is to be used with the chuck 34, the thumb screw 48 is turned back until the chuck can be placed in position, and then it is turned down until the disk 49 engages the chuck, when the apparatus is ready for use, and when the air is to be applied, all that is necessary is to give the thumb screw 48 a few turns to open the valve in the chuck, and the valve, of course, will remain open until it is automatically closed by the spring 38 when it is allowed to act by turning back the thumb nut 48. It will be obvious that the parts 18 and 24 can be used interchangeably as conditions demand.

While I have shown and described my invention as embodied in the form which I at present consider best adapted to carry out its purposes, it will be understood that it is capable of modifications, and that I do not desire to be limited in the interpretation of the following claims except as may be necessitated by the state of the prior art.

45 What I claim as new, and desire to secure by Letters Patent of the United States, is:

1. In a device of the class described, the combination with a body having two passages therethrough, of a fine tube connecting with one end of one passage, the other end of which is provided with means for connecting it to a supply of air under pressure, said means comprising a nipple adapted to co-operate with an air chuck and a thumb screw which can be used to force the air chuck upon the nipple, a coarser tube surrounding the first and connected to one end of the second passage, and a tube connected to the other end of the second passage.

2. In a device of the class described, the combination with a body having two passages therethrough, of a fine tube connecting with one end of one passage, the other end of which passage is provided with means

for connecting it to a supply of air under pressure, said means comprising a nipple adapted to co-operate with an air chuck, a yoke pivoted on the body and provided at its free end with a nut, and a thumb screw 70 screwed through the nut which can be used to force the air chuck on the nipple, a coarser tube surrounding the first and connected to one end of the second passage, and a tube connected to the other end of the 75 second passage.

3. In a device of the class described, a body having a small passage therethrough terminating at the ends thereof in internally threaded enlargements, a fine tube 80 secured in and forming an extension of said passage, means for connection to a compressed air supply threaded into one enlargement, said means comprising a nipple adapted to co-operate with an air chuck and a 85 thumb screw which can be used to force the air chuck upon the nipple, a larger tube surrounding the fine tube and threaded into the other enlargement, said body also having a second passage therethrough terminating 90 at one end in the enlargement into which the tube is threaded and at the other end in a nipple integral with the body for a tube to supply a cleansing liquid.

4. In a device of the class described, the 95 combination with a body having two passages therethrough, of a fine tube connecting with one end of one passage, the other end of which is provided with means for connecting it to a supply of air under pressure, a short coiled spring surrounding the free end of the fine tube, a coarser tube surrounding the first tube and connected to one end of the second passage, said spring 100 engaging both of said tubes to center the fine tube in the coarser one, and a tube connected to the other end of the second passage.

5. In a device of the class described, the combination with a body having three diverging portions, of a nipple forming one 110 of said portions with a passage therethrough, connecting means for supplying compressed air forming a second portion with a passage therethrough, a small tube connected to the inner end of the last mentioned passage, the third portion having a relatively large internally-threaded passage into which the inner end of the first mentioned passage opens, a nut screwed into said threaded passage, a tube carried by said nut and surrounding the small tube and terminating at substantially the same distance from the body as said small tube, and a small helically-coiled spring interposed between the outer ends of said concentric tubes and engaging both of them to center the small tube in the surrounding tube.

In witness whereof, I have hereunto set my hand this 16th day of January, 1922.

WALTER J. RUDOLPH.
